His Attorney

UNITED STATES PATENT OFFICE.

JOHANNES BECKMANN, OF CHARLOTTENBURG, GERMANY, ASSIGNOR TO GENERAL ELECTRIC COMPANY, A CORPORATION OF NEW YORK.

ELECTRIC-FURNACE SYSTEM.

Application filed March 3, 1927, Serial No. 172,446, and in Germany August 19, 1926.

My invention relates to electric furnace systems, more particularly to high frequency electric furnace systems, and has for its object the provision of a simple and reliable system of this character.

It is known, both with a view to improving the power factor as well as to obtain resonance, to place condensers in A. C. networks or circuits in parallel or in series with inductive resistances. This method is of particular importance when the load on the generator is mainly or exclusively an inductive one, such for example, as in high frequency furnaces. Such known connections for high frequency furnaces, however, present various drawbacks. Where the condenser is connected in parallel, the generator only acts upon the condenser if the inductive resistance suddenly drops out, such as in the event of an open circuit in the furnace coil, which entails inadmissibly high voltages owing to excitation of the generator by the leading current taken by the condenser notwithstanding any voltage regulators that may have been provided.

According to my invention these overvoltages are avoided by subdividing the furnace coil and by connecting condensers in parallel with each part of the coil. Should any part of the coil now be interrupted by an open circuit, there still remains the other coil section or sections whose inductive reactance limits the leading current in the generator armature to values which can be handled by the voltage regulator.

The accompanying drawing is a diagrammatic representation of a system of connections embodying my invention.

Referring to the drawing, the furnace coil 1 surrounding the crucible 2 is connected in the circuit 3, connected with any suitable source of A. C. 4. In the form shown, the coil 1 is subdivided into two approximately or exactly equal parts 5 and 6. Condensers 7 and 8 are connected in parallel with the sections 5 and 6 of the coil respectively, a conductor 9 connecting the point of division 10 between the coil sections with a point 11 between the condensers. If desired an

earth connection may be provided for the point of division 10, this connection being through the conductor 9 and conductor 12 leading to ground.

By this system of connections, the generator supplying the furnace is relieved of wattless current. If the condensers are correctly proportioned, an approximate resonance of the oscillating circuit may be brought about. An interruption of a coil 7 or 8 entails no excess voltage, owing to the inductive reactance of the other coil 8 or 7 remaining effective. In such case the generator may also be disconnected by means of overload cutouts, because the current in the non-disconnected half coil rises.

It will be understood that the furnace coil may be divided into more than two sections, if desired, and that these sections may or may not be equal.

What I claim as new and desire to secure by Letters Patent of the United States is:

1. The combination with a high frequency electric furnace, of a high frequency coil therefor divided into sections, and condensers connected across said sections.

2. The combination with a high frequency electric furnace, of a high frequency coil therefor, an intermediate connection dividing said coil into sections, and a condenser connected in parallel with each of said sections.

3. The combination with an electric furnace provided with a high frequency coil, of an electrical connection leading to an intermediate point of said coil, and condensers connected across the portions of said coil on opposite sides of said intermediate point.

4. The combination with an electric furnace provided with a high frequency heating coil, of an earth connection leading to an intermediate point of said coil, and a condenser connected across each portion of said coil.

In witness whereof, I have hereunto set my hand this 14th day of February 1927.

JOHANNES BECKMANN.
